DETECTOR

William M. Christopher, Tonawanda, N. Y., assignor, by mesne assignments, to The Rudolph Wurlitzer Company, Cincinnati, Ohio, a corporation of Ohio

Application October 21, 1935, Serial No. 46,017

11 Claims. (Cl. 194—97)

This invention relates to a detector designed primarily for use in connection with coin controlled vending machines, but it is to be understood that a detector, in accordance with this invention, is for use in connection with any machine or mechanism for which it may be found applicable, and the invention has for its object to provide, in a manner as hereinafter set forth, for automatically detecting blanks, annuli, slugs, discs, or counterfeit coins inserted therein to prevent their travel to a point of destination for the reception of good coins, such destination being a coin controlled mechanism.

A further object of the invention is to provide, in a manner as hereinafter set forth, a detector for preventing the operation of a coin controlled mechanism surreptitiously by the use of slugs, discs, annuli, counterfeit coins or other substitutions which do not have certain configurations of a proper coin of predetermined denomination.

Further objects of the invention are to provide, in a manner as hereinafter set forth, a coin detector which is comparatively simple in its construction and arrangement, strong, durable, readily assembled, automatic in its detecting function, thoroughly efficient in use, and comparatively inexpensive to manufacture.

With the foregoing and other objects which may hereinafter appear, the invention consists of the novel construction, combination, and arrangement of parts as will be more specifically described and as are illustrated in the accompanying drawings wherein is shown an embodiment of the invention, but it is to be understood that changes, variations, and modifications may be resorted to which fall within the scope of the invention as claimed.

In the drawings:

Figure 1 is a rear elevation of the detector as suspended upon the inner face of a support,

Figure 2 is a top plan view of the detector,

Figure 3 is a section on line 3—3, Figure 2,

Figure 4 is a section on line 4—4, Figure 3,

Figure 5 is a side elevation of the form of clutching element employed looking towards the non-working face thereof,

Figure 6 is a central vertical section of the pair of clutching elements forming parts of the detector,

Figure 7 is a section on line 7—7, Figure 3,

Figure 8 is a sectional detail of the coin slide and its supporting and guide means,

Figure 9 is a detail looking towards the top or the bottom of the head part and clutching element of the outer shaft structure, and

Figure 10 is a view of the parts in Figure 9 from each side thereof.

There is illustrated an upstanding support 1 upon which the detector is suspended. The support 1 may be the front of a coin controlled machine in which the detector is installed. The support 1 is formed with a horizontal coin slot 2 of the desired width and length. The support 1 centrally with respect to the top and bottom walls 3, 3^a respectively of the coin slot 2 is provided with oppositely disposed cutouts 4, 4^a respectively (Figures 1 and 8). Secured to the front face of support 1 is an angle-shaped combined retainer support and guide device 5 (Figures 1, 2 and 8) for an angle-shaped coin slide 6 formed at its inner end with a vertical stop 7, intermediate its end with a coin receiving opening 8, and at its outer end with a thumb piece 9. The device 5 includes an angle-shaped upper section formed with a vertical leg 10 and an outwardly directed horizontal leg 11. The device 5 includes a lower section formed of a vertical leg 12 and a horizontal leg 13 extending outwardly from the upper end of leg 12. The latter is of greater length than leg 10. The legs 10, 12 constitute abutments for the stop 7 to prevent the separation of slide 6 from support 1. The leg 13 is of greater length than leg 11 and formed at its sides with inwardly extending oppositely disposed flanges 13 overhanging and spaced from the upper face of leg 12 to form a pair of parallel spaced guide grooves 14 (only one shown) for the slide 6. The flanges 13 at their inner ends abut the ends of leg 10 and constitute retainers for maintaining the slide 6 upon leg 13. The latter is formed with an opening 16 of less diameter than opening 8. The legs 10, 12 are secured against the front of support 1 by the holdfast means 17. The purpose of the slide 6 is to conduct a good coin or a slug, annulus, disc or other spurious substitutions for a good coin to discharge into a combined chute and detection structure 18 which leads to a combined slug detecting, good coin directing, and coin and slug discharging mechanism to be referred to.

The structure 18 includes upper section and lower section 19, 20, respectively. The section 19 has its upper end disposed below the slide 6, when the latter is shifted inwardly with a good coin or spurious substitution for the latter to receive the coin or substitution from the slide. The section 19 extends downwardly at an inclination from its upper end to the upper end of section 20. The latter is vertically disposed.

The section 19 includes a head piece 21 formed with a circular opening 21^a, an upstanding flange

22 at its rear side and a depending apertured flange 23 at its front side. The flange 23 is anchored to the inner face of support 1. The section 19 includes a pair of spaced parallel side rails 24, 25 which merge at their upper ends into the head piece 21. The lower ends of the rails 24, 25 are inturned and merge into the front and rear walls of the upper end of section 20. The bottom edges of the rails 24, 25 have aligning rectangular notches 26, only one of which is shown (Figure 1). Arranged between the rails 24, 25 is a detector element 27 in the form of a weighing scale consisting of a flanged slotted pan 28 having its upper end pivoted on a shaft 29 mounted in the lower end of the rails 24, 25. Extending from the upper end of pan 28 is an outwardly directed downwardly inclined arm 30 carrying at its rear end a fixed counterweight 31. The pan 28 depends below the rails 24, 25 and is provided near its lower end with a pair of oppositely disposed lugs 32 coacting with the notches 26 for limiting or arresting the upward movement of the lower end of pan 28 provided by the counterweight 31. The purpose of the element 27 is to cause the discharge from the section 19 of the chute of a coin or substitution therefor when such coin or substitute is heavier than the weight of that of a good coin. The element 27 is so constructed that the weight of a good coin will not overcome the effect of the counterweight 31 on pan 28 to lower the latter. When the weight of the substitution of a good coin delivered into the section 19 of the chute overcomes the counterweight, the pan 28 is rocked downwardly on its pivot and such substitution is dumped from pan 28 to prevent its being discharged from the lower end of section 19.

The section 20 includes an upper and a lower stretch 33, 34 respectively. The stretch 33 is disposed at right angles to and merges into the upper end of the lower stretch 34. The stretch 33 is directed towards the rails 24, 25. The stretch 33 is formed of a pair of legs 35, 36. The leg 35 extends from and is disposed upwardly at an inclination with respect to leg 36. The leg 35 consists of a pair of sides 37, 38 and a downwardly sloping bottom 39. The leg 36 consists of a vertical rear wall 40, a front wall 41 which inclines away from and is disposed upwardly relative to wall 40, a side wall 42, and a tapered slightly inclined side wall 43. The leg 36 in top plan is of hopper-like contour. The walls 40, 41 merge into the rails 37, 38, respectively, of the leg 35. The wall 40 merges into one side of side wall 43 and into one side of side wall 42. The wall 41 merges into a portion of the length of the lower end of side wall 43. The latter is of greater width than wall 42 and has its lower end spaced from the lower end of rear wall 40. The lower end of leg 36 is of rectangular contour and is provided with an outwardly directed flat flange 44 which seats upon, is secured to and is of the same contour as an outwardly directed flange 45 at the upper end of stretch 34 of section 20. The holdfast means between the flanges 44, 45 is indicated at 46 (Figure 4).

The stretch 34 is of rectangular cross section and includes a rear wall 47, a front wall 48, and a pair of side walls 49, 50 formed lengthwise thereof with slots 51, 52 respectively. The slot 51 is of greater length than slot 52. The lower portions of the walls 49, 50 are of greater thickness than their remaining portions as indicated at 53, 54 respectively. Integral with and depending from the portions 53, 54 are oppositely disposed curved vertical legs 55, 56, respectively, formed at their

lower ends with outwardly directed foot pieces 57, 58, respectively, which are anchored, as at 59, to the base 60 of a supporting structure 61 to be more fully referred to. The stretch 34 is open at its upper and lower ends as is clearly shown in Figure 4. The lower ends of the walls of the stretch 34 are of arcuate contour. The walls 47, 48 have extended therefrom at the upper end of slot 52 a pair of outwardly directed and downwardly inclined apertured ears 62, and a combined detector and deflector element 63 for light coins, slugs, discs, or a substitution for a good coin. The element 63 functions to deflect the light coins in a direction to cause them to discharge from the passage 64 formed by the stretch 34. The light substitutions for good coins are discharged through slot 51. The element 63 includes a lever substantially of semi-oval contour and formed of an outer end part 65 and upper and lower arms 66, 67, respectively, normally disposed at a downward inclination with respect to stretch 34. The arm 66 has its top formed with an upward extension 68 of channel-like form open at each end. The extension 68 is adapted to receive the light substitution for the good coin in its travel downwardly in passage 64. Merging into the upper end of the outer end part 65 is a downwardly inclined threaded bar 68a carrying an adjustable counterweight 68b acting to maintain the lever 63 in the position shown in Figure 4. The arm 66 extends through the upper end of slot 52 in a downwardly inclined direction towards the slot 51 below the upper end of the latter. The slot 51 extends above the upper end of slot 52. The upper end of the outer end part 65 is arranged between the ears 62 and is loosely mounted on a pivot 68c carried by ears 62. The arm 67 has its free end normally abutting the wall 50 below the bottom of slot 52 and constitutes a stop for limiting the shifting movement of lever 63 by the counterweight 68b and to provide for arm 66 to extend across the passage 64 in the path of the coins and substitutions for the latter. When a good coin or a substitution for the latter corresponding in weight to the good coin travels downwardly in passage 64 and impacts arm 66, the latter will be lowered and swung outwardly to an extent to permit for the good coin or substitution to continue its travel in a direction to be discharged from the lower end of stretch 34. When the substitution for a good coin is of less weight than the latter, it does not rock lever 63 and is deflected through slot 51.

The good coin substitution, whether it be a solid disc, slug, blank or counterfeit or an annulus or an apertured disc, slug or blank, will be hereinafter referred to as slug.

The combined slug detecting, good coin directing and coin and slug discharging mechanism acts upon a slug, which has passed through stretch 35 of element 18, to prevent it from being directed to the point of destination for a good coin and which also acts to direct the good coin into a conducting means leading to the point of destination for the good coin. The said mechanism is mounted on the supporting structure 61 and the latter will not be referred to. The base 60 of the structure 61 has a thickened intermediate portion 69, a forward vertical arm 70 at the front end of base 60, a rear vertical arm 71 at the rear end of base 60 and of less height than arm 70, a vertically disposed L-shaped bracket 72 having its horizontal leg integral with the rear face of arm 71 above the bottom of the latter and

its vertical leg extended above the upper end of arm 71, and a pair of spaced parallel intermediate arms 73, 74 integral with the ends of the thickened portion 69. The arm 73 is of greater height than arms 71, 74 and is arranged in parallel spaced relation to arm 71. The arm 74 is of less height than and is disposed in parallel spaced relation to arm 70. The latter is suitably anchored to the inner face of support 1. The arm 10 70 is formed with an opening 75 which registers with an opening 76 formed in support 1. The arm 74 has an opening 77 of greater diameter than and which aligns with opening 75. The arm 73 is formed with an opening 78 of less diameter than 15 and which aligns with opening 77. The arm 71 has an opening 79 of less diameter than and which aligns with opening 77. The vertical leg of bracket 20 72 is formed with a threaded opening 80 which aligns with opening 79. The vertical leg of bracket 25 72 is reduced at its upper end, as at 81, and formed with an opening 82 which aligns with an opening 83 formed in the upper end of arm 73. The thickened portion 69 of base 60 is formed with a transversely extending flared slot 84, a concavity 85 (Figures 3 and 7) in its upper face 25 between slot 84 and arm 73, a depending tubular part 86 on its lower face between slot 84 and arm 73, and an opening 87 which communicates with concavity 85 and part 86.

30 The slug detecting and good coin directing and coin and slug discharging mechanism includes a shaft 88 having a collar 89 fixed thereto intermediate its ends. The shaft 88 is the operating shaft of said mechanism and at its outer end is fixed 35 to a turning knob 90 therefor arranged exteriorly of support 1. The knob 90 is formed in its inner face with a socket 91 into which extends a stationary bearing 92 for the knob. The bearing 92 is of cap-shaped form and encloses a stationary 40 annulus 93 which encompasses in spaced relation the collar 89. A controlling spring 94 for the shaft 88 is interposed between and fixed to the collar 89 and annulus 93. The bearing 92 and annulus 93 are connected together by spaced holding 45 fast means 95 which engage in the support 1 for anchoring the bearing and annulus stationary against the outer face of support 1.

Encompassing, slidably coupled to, and revolved 50 by the shaft 88 is a slidable spring controlled revoluble outer shaft structure 96 for carrying and shifting a front clutching element to be referred to. The structure 96 includes an outer tubular part 97, an intermediate part 98 and a head 99. The inner portion of the part 97 is of greater 55 outer diameter than the remaining portion thereof and corresponds in outer diameter to that of the said part 98. The head 99 is of materially greater diameter than and is disposed concentrically with respect to part 98. The part 97 merges into the part 98. The latter merges into the head 99. The part 97 is slidably mounted on shaft 88, extends into the openings 75, 76 and is formed at the inner end of its portion of smallest outer diameter with a pair of diametrically disposed slots 100 lengthwise thereof. The shaft 88 is provided with a diametrically extending pin 101 for coupling the shaft structure 96 therewith to provide for the revolving of the latter on the operation of shaft 88. Carried by that portion of part 60 97 of smallest outer diameter is a flanged collar 102 and a fixed annular abutment 103 arranged in spaced relation to the collar 102. The latter is shiftable lengthwise on part 97. The pin 101 extends into collar 102 and constitutes a stop to 65 collar 102 when the latter is shifted in a direction

towards head 99. Interposed between collar 102 and abutment 103, as well as encompassing part 97, is a coiled controlling spring 104 acting to return shaft structure 96 to its normal position, such as shown in Figure 3. The head 99 consists of a circular body part 105 having a cam face 106 coacting with a stationary cam 107 fixed to arm 74 to provide for the shaft structure 96 being shifted inwardly on the operation of shaft 88 from knob 90. The other face of body part 105 has extending therefrom upper and lower oppositely disposed semi-circular flanges 108, 109 respectively. The flange 108 is of less width than the flange 109 and encompasses an edge portion of a front clutching element 110 to be referred to. The flange 109 encompasses and extends beyond the remaining edge portion of element 110. The flange 109 constitutes a support for a good coin or a slug. The front clutching element is designated 110 and includes (Figure 6) a disc 111 which opposes the rear face of body part 105. The disc 111 is formed with an axially arranged opening 112 in which is countersunk the head of a screw 113 threadedly engaging with the wall of a threaded socket 114 formed axially of the shaft structure 96 and opening at the rear face of head part 105. The disc 111, in proximity to its outer edge is formed with a circular row of spaced openings 115 in which are slidably mounted combined finder and clutch pins 116 having bearing against the heads thereof, spaced radially disposed resilient arms 117 (Figures 5 and 6) of a carrier 118 mounted axially thereof upon the screw 113. Secured upon the latter and bearing against the carrier 118 is a binding nut 119 for clamping the central portion of the latter against the central portion of the disc 111.

Aligning in spaced relation with respect to the shaft structure 96 is a spring controlled adjustable revoluble rear shaft structure 120 including a shaft 121 formed of a front part 122 and a rear part 123 of less length and diameter than that of part 122. The junction of the parts 122, 123 form shaft 121 with a peripheral shoulder 124. The parts 122, 123 are mounted respectively in the openings 78, 79. The front end of front part 122 is integral with the rear face of a disc-like head part 125 formed at its edge with a cam 126 best shown in Figure 7. The purpose of cam 126 will be presently referred to and its normal position thereof is as shown in Figures 2 and 7. Carried by and arranged in spaced relation to the front face of head part 125 is a rear clutching element 127 constructed in the same manner as and oppositely disposed with respect to clutching element 110. The element 127 is secured to head part 125 in the same manner as clutching element 110 is secured to head part 105. The part 123 has mounted in its rear end a thrust bearing 128 of globular form which abuts the front end of a peripherally threaded adjusting member 129 for shaft 121. The member 129 extends through and has threaded engagement with the opening 80 in the vertical leg of bracket 72. A holding nut 130 is carried by member 129 exteriorly of said vertical leg. The latter and the arm 73 are connected together by a threaded tie rod 131 which is seated in opening 83, extended through opening 82, and carries a pair of securing nuts 132 abutting the front and rear faces of the reduced part 81 of the vertical leg of bracket 72. The shaft 121 revolves in the openings 78, 79 against the action of a controlling spring 133 having one end fixed to part 122, as at 134, and its other end extended and passed 70 75

through rod 131, as at 135. The slidably mounted combined finder and clutch pins of the element 127 are indicated at 136.

The finder and clutch pins of the clutching elements are so arranged and constructed that they will catch on certain letters or engravings on the good coins for the purpose of gripping the coins so that the shaft structures 96, 120 will be clutched to simultaneously revolve whereby 10 a deflector device, to be referred to, will provide for the good coins to travel in a direction towards the point of destination therefor. The finder and clutch pins will not clutch and associate with the faces of the slugs in a manner 15 to provide for clutching the shaft structures 96, 120 together to cause them to revolve in unison. When the structures 96, 120 are not clutched together, the slug carried by the head part of shaft structure 96 will be discharged from the 20 latter on the revolving of the structure 96 independent of structure 120. The deflector device normally closes the conducting off means, to be referred to, for the good coins and is operated to open said conducting off means by the cam 25 126. The deflector device also constitutes means to prevent the slugs from travelling in the direction provided for the good coins. The deflector device indicated generally at 137 and best shown in Figure 7 includes a vertically movable 30 plunger 138 arranged in the tubular part 86 and opening 87 and normally extending into the cavity 85 in the path of the cam 126 on the edge of the head part 125. The lower end of plunger 138 merges into an inclined arm 139 having a 35 lower end terminal portion 140 (Figure 3) disposed at right angles to the remaining part of arm 139 and extended through an opening 141 formed in the small end 142 of a substantially triangular shaped plate 143, which in proximity 40 to opening 141 is fixed to a rock shaft 144, carrying a deflector member 145 (Figure 4) formed of a lower horizontal leg 146 and an upstanding leg 147 of greater length than leg 146. The plate 143 also acts as a counterbalance for shaft 45 144 due to the fact that the latter is connected to the plate 143 eccentrically of the latter. The leg 147 extends through and is anchored to shaft 144. The leg 146 extends from the lower end of leg 147 and is arranged below shaft 144. 50 Anchored to the base 60 is an upstanding stop member 148 formed at its upper end with an inwardly extending leg 149 arranged in the path of cam 126 for arresting the upward travel thereof. 55 Secured to and depending from the base 60 is a hollow directing element 150 of frusto-tapered contour formed of a body part 151 merging at its bottom into a pair of oppositely disposed outwardly directed inclined branches 152, 153 to 60 which are coupled or secured, as at 154, a good coin directing chute and a slug carrying off chute 155, 156, respectively. The chute 155 is adapted to lead to the point of destination, not shown, for a good coin. The chute 156 is shown, by way 65 of example, as leading to and discharging into a slug receiver 156^a (Figure 1) arranged at the front of support 1. The bottom of the body part 151 and the inner side of branch 152 are open, as at 156^b, to provide a clearance for leg 147 of 70 member 145. The shaft 144 extends through the body part 151 in proximity to the bottom of the latter. The member 145 is arranged in body part 151. The upper end of body part 151 registers with the slot 84. The normal position of leg 146 of member 145 is as shown in dotted lines, Fig-

ure 4, whereby branch 152 is closed. When cam 126 depresses plunger 138 (Figure 7), shaft 144 is rocked in a direction to move member 145 to the full line position (Figure 4) whereby branch 153 is closed and leg 147 swung into the branch 152 to be positioned in the path of the good coin, the latter impacts leg 147 which in connection with the plate 143 will cause the shaft 144 to be rocked in the opposite direction moving member 145 to the dotted line position (Figure 4), closing branch 153, and opening branch 152 whereby the good coin will be permitted to pass from branch 152 into chute 155.

To prevent a pair of coins or slugs or a coin and a slug being supported simultaneously by the flange 109 of head part 99 of structure 96, a stop lever 157 (Figure 4) is employed. The lever 157 at its upper end is formed with a projection 157^a which, when lever 157 is in active position, depends below the lower end of stretch 34 to be 20 arranged rearwardly of clutching element 110 (Figures 3 and 4). The projection 157^a prevents a coin or slug to be positioned between a coin or slug and the clutching element 110. The lever 157 is of arcuate contour and arranged forwardly of wall 48 and leg 56 of stretch 34. The lever 157 is pivoted at its lower end, as at 158, to a lateral lug 159 on leg 56. The pivoted end of lever 157 is formed with an angularly disposed nose 160 arranged in the path of the end edge 161 of flange 109. The upper end of lever 157, when the latter is active, engages under an offset part of a stop member 162 secured to the front face of wall 48 of stretch 34. When shaft structure 96 is revolved by shaft 88, the edge 161 of flange 109 engages the nose 160 and shifts lever 157 upwardly whereby the projection 157^a is swung clear of the pins of clutching element 110. The edge 161 maintains the lever 157 elevated until shaft structure 96 is returned to its inactive position. As shaft structure 96 is moved to its inactive position, lever 157 lowers by gravity until it assumes the position shown in Figure 4. To limit the upward shift of the lever 157, the wall 48 of stretch 34 is provided on its front face with a stop 162^a (Figures 3 and 4) positioned in the path of the top edge of the lever. The latter on the front face thereof and directly above projection 157^a is weighted, as at 163, to assist in the lowering of the lever to normal position. 50

To prevent the passage of an axially apertured slug or a coin substitution in the form of an annulus upon the detector element 27 is a detector 164 consisting of an upwardly disposed inwardly inclined rod 165 having its upper end arranged at the opening 21^a in head 21 (Figures 1 and 2). The opening 21^a is of greater diameter than that of a good coin or slug. The upper end of rod 165 constitutes a support for and a stop to arrest a good coin or solid slug from dropping through opening 21^a. If an axially apertured slug or a coin substitution in the form of an annulus is discharged from slide 6 over opening 21^a, it will be taken up by rod 165 and pass downwardly on and be retained by the rod. The rod 165 is removably supported by the overlapped slotted upper part 166 of an inwardly inclined bracket 167 secured to the inner face of support 1 below the head 21. The rod 165 has a laterally extended combined stop and lifting bar 168 adjacent its lower end. The bar 168 seats on a washer 169 on the upper end of bracket 167. 60

The operation of the combined slug detecting, good coin directing and coin and slug discharging mechanism will now be referred to. The 70 75

coin or slug travels down the chute-like stretch 34 of section 20. If the slug is of light weight it will be deflected by the arm 66 of element 63 from the stretch 34 through slot 51. The coin 5 will depress arm 64 and pass into the lower portion of stretch 34. The slug will do likewise if the weight thereof corresponds to that of the coin. The coin or the slug passes from stretch 34 and falls upon the semi-circular projection or 10 flange 109 at the inner end of structure 96. The projection 109 is normally held at the bottom of the structure 96 by the spring controlled knob 90. When the coin or slug is deposited in projection 109 it is arranged between the elements 15 110, 127, and the cam 126 is up against the leg 149 of stop member 148. Now by turning knob 90 to the right, it also turns structure 96 and causes the latter to be shifted inwardly to provide for the coin or slug to be engaged by the 20 pins 116, 136. The inward shift of the structure 96 is had through the medium of cam 107 acting upon body part 105. When the structure 96 makes one-half turn, it springs back by the pressure of spring 104 and releases the coin or 25 slug. When the projection 109 is at the top of structure 96 and the coin or slug released, the coin or slug then drops through slot 84 into the chute-like directing element 150. The knob 90 makes only one-half turn and is forced back by 30 the spring 94. The knob 90 operates shaft 88. The structure 96 turns in unison with shaft 88 and knob 90. The clutching elements 110 and 127 are fastened solid to the structures 96, 120 respectively. When a coin is deposited upon 35 projection 109 and knob 90 turned to the right, the pins 116, 136 catch on the lettering or engraving on each side of the coin and which will provide for the structures 96 and 120 turning in unison. On the turning of structure 120 the cam 40 126, which is fixed to and moves with the structure 120 pushes down the plunger 138, which in turn will actuate the arm 139 whereby element 145 will be shifted to a position to permit of the coin passing into branch 152 of the element 45 150. If a slug with smooth side faces was deposited upon projection 109, the pins or feelers would not catch in the side faces of the slug and under such conditions the structure 120 would not turn and operate element 145 whereby 50 when the slug is discharged from projection 109 it will pass through slot 84 into element 150 and be conducted off through branch 153.

The purpose of the projection 157^a of the lever 55 157 is to keep a leading coin or slug straight up and down when it is supported by the projection or flange 109. This provision prevents a following coin or slug passing between the pins 116 and the supported coin or slug in case the latter 60 has not been discharged. The weight 163 functions to normally maintain the lever 157 in the position shown in Figure 4 whereby the projection 157^a will hold a coin or slug deposited on the projection or flange 109, in opposed relation 65 to the pins 116 and in line with the passage of section 20. When structure 96 is turned from normal position for the purpose referred to, an end edge of the projection or flange 109 will engage the nose 160 on the lever 157 and the latter 70 will be raised to an extent to have its projection 157^a moved clear of the element 110. When structure 96 is returned to its normal position, the lever 157 due to the action of the weight 163 is returned to the position shown in Figure 4.

75 What I claim is:

1. In a detector for separating certain coins having the usual side face configurations from imperforate and smooth sided slug imitations thereof, a director including a coin directing means, a slug directing means and controllable means common to said directing means for normally closing the coin directing means and normally opening the slug directing means, a coin and slug receiving mechanism arranged over and having a discharge slot opening into said director, said mechanism including a slidable revoluble front shaft structure and a revoluble non-slidable rear shaft structure, said front structure including means, on the revolving thereof in one direction, for dumping a coin or slug 10 into said slot, said structures including means controlled by the configurations of the coin to provide for the revolving thereof in unison, said rear structure including means acting, during the revolving thereof in one direction, upon said 15 controllable means for opening the coin directing means to receive the coin and for closing the slug directing means, means for sliding the front structure in a direction towards the rear structure on the revolving of the front structure, and means for revolving the front structure. 20

2. In a detector for separating certain coins having the usual side face configurations from imperforate and smooth sided slug imitations thereof, a director including a coin directing means, a slug directing means and controllable means common to said directing means for normally closing the coin directing means and normally opening the slug directing means, a coin and slug receiving mechanism arranged over and having a discharge slot opening into said director, said mechanism including a slidable revoluble front shaft structure and a revoluble non-slidable rear shaft structure, said front structure including means on the revolving thereof in one direction for dumping a coin or slug 30 into said slot, said structures including means controlled by the configurations of the coin to provide for the revolving thereof in unison, said rear structure including means acting during the 35 revolving thereof in one direction upon said controllable means for opening the coin directing means to receive the coin and for closing the slug directing means, means for sliding the front structure in a direction towards the rear structure on the revolving of the front structure, and means for revolving the front structure, the said 40 means controlled by the faces of the coin including spaced yieldingly controlled slidably mounted finder and clutch pins. 45

3. In a detector for separating certain coins having the usual side face configurations from imperforate and smooth sided slug imitations thereof, a director having a pair of oppositely extending controllable directing means respectively for a coin and a slug, a coin and slug receiving mechanism including a revolvably mounted slidable front shaft structure and a revoluble rear shaft structure disposed in endwise spaced alignment, said mechanism discharging into said director, said director including means common to said pair of directing means for alternately opening the coin directing means and closing the slug directing means, said structures including means controlled by a coin for revolving the structures in unison and said rear structure including means for operating said common means to close the slug directing means and open the coin directing means. 55

4. In a detector for separating certain coins having the usual side face configurations from imperforate and smooth sided slug imitations thereof, a director having a pair of oppositely extending controllable directing means respectively for a good coin and a slug, a good coin and slug receiving mechanism including a revolvably mounted slideable front shaft structure and a revolvably rear shaft structure disposed 10 in endwise spaced alignment, said mechanism discharging into said director, said director including means common to said pair of directing means for alternately opening the coin directing means and closing the slug directing means, said structures including means controlled by a good coin for revolving the structures in unison and said rear structure including means for operating said common means to close the slug directing means and open the good coin directing means, said structures being spring controlled, means for revolving said front structure, and said mechanism including means to provide 20 for the sliding of the front structure towards the rear structure on the revolving of the latter.
- 25 5. In a detector for separating certain coins having the usual side face configurations from imperforate and smooth sided slug imitations thereof, a director having a pair of oppositely extending controllable directing means respectively for a coin and a slug, a coin and slug receiving mechanism including a revolvably mounted slideable front shaft structure and a revolvably rear shaft structure disposed in endwise spaced alignment, said mechanism discharging into said 30 director, said director including means common to said pair of directing means for alternately opening the coin directing means and closing the slug directing means, said structures including means controlled by a coin for revolving the structures in unison and said rear structure including means to close the slug directing means and open the coin directing means, said front structure at its inner end being provided with a support for 35 the coin or slug, and means arranged over said front structure to prevent the passage of a coin or slug to the support when the latter has seated thereon a coin or slug.
- 40 6. In a detector for separating certain coins having the usual side face configurations from imperforate and smooth sided slug imitations thereof, a director having a pair of oppositely extending controllable directing means respectively for a coin and a slug, a coin and slug receiving mechanism including a revolvably mounted slideable front shaft structure and a revolvably rear shaft structure disposed in endwise spaced alignment, said mechanism discharging into said 45 director, said director including means common to said pair of directing means for alternately opening the coin directing means and closing the slug directing means, said structures including means controlled by a coin for revolving the structures in unison and said rear structure including means to close the slug directing means and open the coin directing means, the said means for operating said common means being in the form of a cam travelling in a circular path, and means for limiting the 50 travel of the cam.
- 70 7. In a detector for separating certain coins having the usual side face configurations from imperforate and smooth sided slug imitations thereof, a pair of endwise aligning spaced revolvably spring controlled shaft structures each in-

cluding a clutching element, said elements being disposed in parallelism for opposing a coin or a slug deposited therebetween on one of said structures, said elements including slideable yieldingly controlled pins coacting with the configurations of the coin for clutching said structures together to provide for the revolving thereof in unison to discharge the coin, a movable coin deflector operable upon the revolving of said structures in unison, and one of said structures including means on the revolving thereof for shifting it towards the other structure for positioning said pins in clutching engagement relative to the configurations of the coin and in non-clutching engagement relative to the slug.

15 8. In a detector for separating certain coins having the usual side face configurations from imperforate and smooth sided slug imitations thereof, a pair of endwise aligning spaced revolvably spring controlled shaft structures each including a clutching element, said elements being disposed in parallelism for opposing a coin or a slug deposited therebetween on one of said structures, said elements including slideable yieldingly controlled pins coacting with the configurations of the coin for clutching said structures together to provide for the revolving thereof in unison to discharge the coin, one of said structures including means on the revolving thereof for shifting it towards the other structure for positioning said pins in clutching engagement relative to the configurations of the coin and in non-clutching engagement relative to the slug, that structure upon which the slug is deposited being independently revolvable of the other structure when the pins are 25 in non-clutching engagement with the slug to discharge the latter, a support for said structures having a discharge slot arranged between said structures, said slot being common to the coin and slug, and a director common to the coin and slug, 30 registering with said slot and formed with a normally closed coin directing and a normally open slug directing means, and means slidably extending through said support, arranged in said director and operated from and on the revolving 35 of said non-slideable shaft structure for simultaneously opening and closing respectively the coin and slug directing means.

40 9. In a detector for separating certain coins having the usual side face configurations from imperforate and smooth sided slug imitations thereof, a pair of revolvably shaft structures having spaced, opposed clutching elements adapted to receive a coin or slug therebetween, means for revolving one of said structures, means operable by the revolving of said structure for reducing the space between the structures, said clutching elements including means for engaging the side face configurations of an interposed coin when the space is so reduced to cause said structures 45 to revolve in unison, and a movable coin deflector operable upon the revolving of said structure in unison.

50 10. In a detector for separating certain coins having the usual side face configurations from imperforate and smooth sided slug imitations thereof, a pair of revolvably shaft structures having spaced, opposed clutching elements adapted to receive a coin or slug therebetween, means for revolving one of said structures, means operable by the revolving of said structure for reducing the space between the structures, said clutching elements having means slideable over a smooth sided slug interposed therebetween but engageable by the side configurations of a coin interposed there- 55

between to provide for the revolving of said structures in unison when the space is so reduced with a coin so interposed and to further provide for revolving but one of said structures when a 5 smooth sided slug is so interposed, and separate means controlled by the revolving of said structures in unison for receiving coins and slugs.

11. In a detector for separating certain coins having the usual side face configurations from 10 imperforate and smooth sided slug imitations thereof, a director having a pair of oppositely extending controllable directing means respectively for a coin and a slug, a revolvable coin and slug receiving structure discharging the coin or slug

into the said director, said director including means common to said pair of directing means for alternately opening the coin directing means and closing the slug directing means, said structure including a pair of opposed sections adapted to be clutched together by a coin to provide for the revolving of both of said sections and coin in unison upon the revolving of one of said sections, and means actuated by the revolving of the other of said sections for operating said common means for closing the slug directing means and opening the coin directing means. 5
